U.S. Appl. No. 11/651,747, filed Jan. 10, 2007, Schmidt.

Primary Examiner—Holly H Baynham

(74) *Attorney, Agent, or Firm*—Mueting, Raasch & Gebhardt, P.A.

(57) **CLAIM**

The ornamental design for a cup portion of a wallpaper border support and applicator tool, as shown and described.

DESCRIPTION

The subject matter disclosed herein is related to subject matter disclosed in U.S. patent application Ser. No. 11/651,747, filed on even day herewith, which is incorporated herein by reference in its entirety.

FIG. 1 is a perspective view of a cup portion of a wallpaper border support and applicator tool in accordance with one embodiment of the invention, the tool shown with a border support shaft illustrated in broken lines;

FIG. 2 is a perspective view thereof with the border support shaft removed;

FIG. 3 is a left side elevation view thereof, the right side elevation view being a mirror image of the left side elevation view;

FIG. 4 is a top plan view thereof;

FIG. 5 is a top plan view thereof with the border support shaft removed;

FIG. 6 is a bottom plan view thereof;

FIG. 7 is a front elevation view thereof;

FIG. 8 is a quarter section view thereof taken along line 8—8 of FIG. 4;

FIG. 9 is a section view thereof taken along line 9—9 of FIG. 4; and,

FIG. 10 is a rear elevation view thereof.

All of the material from the utility application which is essential to the claimed design is included herein. Any material in the utility application which is not present herein forms no part of the claimed design.

The broken line renderings of the border support shaft in FIGS. 1, 3, 4, and 7—10, as well as the broken line renderings of the cup portion shown in FIG. 10, depict environment; the features shown in broken lines in the figures are for illustrative purposes only and form no part of the claimed design.
